UNITED STATES PATENT OFFICE.

GEORGE FARR AND ALBERT B. SEWARD, OF CINCINNATI, OHIO; SAID
SEWARD ASSIGNOR TO EDWARD W. FARR, OF PEORIA, ILLINOIS.

SMOKE-PREVENTING FURNACE.

SPECIFICATION forming part of Letters Patent No. 317,935, dated May 12, 1885.

Application filed November 13, 1882. (No model.)

To all whom it may concern:

Be it known that we, GEORGE FARR and ALBERT B. SEWARD, both of Cincinnati, Hamilton county, and State of Ohio, have invented 5 certain new and useful Improvements in Smoke-Preventing Furnaces, of which the following is a specification.

Our invention is applicable to boiler and other stationary furnaces, or to locomotives; 10 and its object is to prevent the formation of smoke by consuming the smoke-forming gases before they escape from the fire-chamber.

Referring to the drawings forming part of this specification, Figure 1 is a plan view of 15 the fire-chamber, showing the preferred form of our invention to be employed in connection with a stationary-boiler furnace, the boiler and upper part of the walls being removed. Fig. 2 is a vertical transverse section through the 20 fire-chamber shown in Fig. 1 at the dotted line x of the latter figure, the boiler and walls being present. Fig. 3 is a plan view of a furnace, showing a modification of our invention 25 as illustrated by Fig. 1. Fig. 4 is a transverse vertical section of the furnace shown in Fig. 3, and taken at the dotted lines y of the latter figure. Fig. 5 represents the application of 30 our invention to a locomotive. Fig. 6 is an enlarged detail view of one portion of our invention.

A A are the side walls of the furnace, A' the fire-chamber, A² the ash-pit, and A³ the boiler.

The fire-chamber is provided with the ordinary grate-bars, a , which may be of any desired 35 form.

In each of the side walls A, and somewhat above the grate-bars, is a flue, B, extending nearly the entire length of the fire-chamber. A flue, 40 B', preferably vertical, communicates with this flue B and opens into the ash-pit, as shown, and a short flue or opening, B², establishes communication between this flue B' and the outside air. Heated air from the ash-pit and 45 cold air from the outside are thus mingled in the flue B' before entering the flue B. When preferred, air may be introduced from the ash-pit or the outside separately, as desired.

Several openings, b , establish communication 50 between the flue B and the fire-chamber

at either side, the number of these openings varying with the length of the fire-chamber, in the present instance four of these openings being shown at either side of the fire-chamber. These openings are preferably "staggered," 55 as shown—that is, the openings at one side of the chamber are opposite the space between the openings at the opposite side.

In the flues B, opposite each one of the openings b , is placed a metallic box or conduit, 60 C, (preferably of cast iron,) the ends of which are open to allow air to freely circulate in the flue B. In the side of each one of these boxes which is toward the opening b is a conduit connecting the interior of the box C with the 65 opening b , and this conduit is preferably constructed as follows: One end of a short tube, B, is connected to the box C near the center of the latter, and opens into the cavity of said box. The other end of this tube extends part 70 way through the opening b toward the fire-chamber.

At one side of the flues B, and preferably parallel thereto, are the pipes E, preferably located in the side walls, as shown in Figs. 1 75 and 2, and communicating in any desired manner with the steam-space of the boiler. These pipes E are provided, opposite each of the boxes C, with jets or nipples e, each of which passes through the outer side of the box C, the end 80 extending a slight distance into the end of the tube D, which is within the box C, as shown in Fig. 6, a space being left between the outer side of the end of the nipple and of the inner surface of the tube, to permit air to pass through 85 the tubes D from the boxes C. The ends of these jets e discharge, preferably, in the same horizontal plane, so that the steam which passes through each jet will be carried across the fire-chamber in a plane above and parallel 90 to the plane of the grate-bars.

The manner in which our invention as above described operates is as follows: Fire having been started in the furnace and steam being supplied from a suitable source, steam is allowed to enter the pipes E, from which it passes through the jets e into the fire-chamber 95 in a direction toward the opposite wall. As the steam passes from the jets e through the tubes D it causes a draft of air through the 100

flues B', B², and B, and through the boxes C and tubes D, and thus the air is mingled with the steam coming from the jets e just before entering the fire-chamber. This combined 5 steam and air is driven across the furnace, the jets from the one side of the furnace alternating in position with the jets from the opposite side, forming a complete sheet of steam and air above the fire-line, and the gas arising 10 from the burning fuel is caught by this sheet of steam and air and driven toward the sides of the chamber, in which positions it is consumed before the smoke is fairly formed, the combustion taking place uniformly through 15 out the entire length of the fire-chamber.

The tendency of the smoke-consumers heretofore employed has been to concentrate the heat at a certain limited point, and to compel all the smoke to pass over this point, causing 20 it to be here consumed. The objection to this is that too great heat is applied to the boiler at a limited point, and the boiler is thus very quickly burned out at this point.

The sheet of air and steam formed by the 25 jets e of our invention compel an almost uniform distribution of the heated area throughout the entire chamber, said area being in a plane above and parallel to the fire-line, the point of the greatest heat, however, being at 30 the sides of the chamber, and when the furnace is a boiler-furnace at the point of greatest distance between the grate-bars and the boiler, so that the heat is thus uniformly distributed to the boiler throughout the entire extent of 35 the fire-chamber, thus not endangering the boiler.

When our invention is applied to a furnace at the time it is built, the pipes E are preferably placed in the walls, as shown in Figs 1 40 and 2; but when applied to a furnace after it has been built these pipes may be placed outside of the walls, as shown in Figs. 3 and 4, the boxes C being placed in the flues B within the walls, as in the former instance. In either 45 event the operation of our invention will be precisely the same.

If desired, the boxes C may be omitted, or rather modified in form, a plate, C', being placed in front of that end of the openings b 50 which adjoins flue B, in which plate the short tubes D are secured, as in the sides of the boxes, the other features of the invention remaining the same.

When applying our invention to locomotive-boiler furnaces, the arrangement shown in 55 Fig. 5 will be substantially observed. In this

instance both the pipes E and the boxes C are placed outside the walls of the furnace, the boxes being supported by appropriate brackets or angle-irons, as d, secured to the outside 60 shell of the locomotive. A pipe or tube, F, passes through the water-leg G of the locomotive, which tube serves the purpose of the openings b, and into the outer end of this tube the ends of the short tubes D are in- 65 serted, as shown.

The principle and operation of our invention, whether used in connection with stationary or locomotive-boiler furnaces, is, as will be observed, precisely the same. 70

One end of each of the pipes E is provided with a cock, f, to enable the pipes to be blown out or cleaned.

When desired, the jets, flues, and pipes may be confined to one side of the furnace; but this 75 mode of arrangement is not desirable, as the jets must be greatly increased in number to accomplish the purpose desired, and the combustion would be more particularly confined to that side of the furnace which is opposite 80 the jets.

The various features of our invention are preferably used together, but one or more may be used together or separately, or in connection with smoke-preventing devices to which 85 they may be applicable.

Having thus described our invention, what we claim as new, and desire to secure by Letters Patent, is as follows:

1. The flues B, located at the sides of the 90 fire-chamber and having inlet-flues B' B² and openings b, communicating with the fire-chamber, in combination with the tubes D, extending into the openings b, and the supporting-plate C', and the steam-pipes E, having 95 jets e extending into the ends of tubes D, substantially as and for the purposes specified.

2. The flues B, located at the sides of the fire-chamber and having inlet-flues B' B² and openings b, communicating with the fire-chamber, in combination with the boxes C, located 100 in the flues B, and provided with the tubes D, extending into the openings b, and the steam-pipes E, having jets e extending into the ends of the tubes D, substantially as and for the 105 purposes specified.

GEORGE FARR.
ALBERT B. SEWARD.
